UNITED STATES PATENT OFFICE.

GEORGE W. BOWEN, OF AUBURN, NEW YORK.

CAP FOR LUBRICANT-CUPS.

No. 918,285.

Specification of Letters Patent.

Patented April 20, 1909.

Original application filed February 23, 1905, Serial No. 246,834. Divided and this application filed August 14, 1908.
Serial No. 448,470.

To all whom it may concern:

Be it known that I, GEORGE W. BOWEN, of Auburn, in the county of Cayuga and State of New York, have invented a certain new and useful Cap for Lubricant-Cups, of which the following is a specification.

My invention has for its object the production of a cap for a lubricant cup, which is particularly simple in construction and economical of manufacture, and is especially applicable for use with the body of a lubricant cup set forth in my application, Sr. No. 246,834, filed February 23, 1905, of which the present case is divisional; and to this end, it 10 consists in the novel features of construction hereinafter set forth and claimed.

In describing this invention, reference is had to the accompanying drawing in which like characters designate corresponding parts 20 in all the views.

Figure 1 is an elevation of a lubricant cup comprising a cap embodying my invention, Fig. 2, is a vertical sectional view thereof. Fig. 3 is a top plan, partly broken away, of 25 my cap. Fig. 4 is an isometric view of said cap.

The base 1 of the lubricant cup illustrated in the drawings is preferably formed of sheet metal, but as the construction of said base is 30 set forth in my pending application aforesaid, and forms no part of my present invention, further description thereof herein is deemed unnecessary.

The cap 2 forming the subject-matter of 35 my present invention is provided with a knurled hand-engaging portion formed by distorting the metal of said cap, thereby causing said hand-engaging portion to project from the adjacent part of the cap. As 40 best seen in Fig. 3, said hand-engaging portion consists of a plurality of peripheral projections or corrugations 3, preferably formed hollow, spaced equal distances apart, and extending from substantially the junction of 45 the top 4 and the peripheral wall 5 of the cap 2, said projections 3 being formed by distorting and spreading portions of the sides of the cap outwardly laterally relatively to the adjacent parts of the cap, by pressure acting 50 on the interior of the cap in a direction substantially radially relatively to the axis of the cap. Said cap may be provided with internal threads for securing the same to the base 1.

The cap 2 is formed from a sheet metal shell, the peripheral projections 3 being 55 formed by crushing the crown of the shell and holding the major portions of the barrel thereof and the portions alternating with said projections, from contracting or spreading, thereby forcing outwardly parts of the 60 shell along the line of union of the crown and barrel thereof.

As is obvious, a cap for a lubricant cup constructed as described, may be manufactured quickly, cheaply and with minimum labor.

The construction of my cap for lubricant cups will now be readily understood upon reference to the foregoing description and the accompanying drawing.

What I claim, is:—

1. As a new article of manufacture, a cap for a lubricant cup, the cap being composed of sheet metal and having a portion of the metal forming the same distorted to project 75 from the contiguous part of said cap to provide a hand-engaging portion, substantially as and for the purpose specified.

2. As a new article of manufacture, a cap for a lubricant cup, the cap being composed 80 of sheet metal and having portions of the metal forming the same distorted to project from contiguous parts of said cap to provide a hand-engaging portion, substantially as and for the purpose specified.

3. As a new article of manufacture, a cap for a lubricant cup, the cap being composed 85 of sheet metal and having hollow peripheral projections spaced apart, substantially as and for the purpose described.

4. As a new article of manufacture, a cap for a lubricant cup, the cap being composed 90 of a single piece of pressed sheet metal and having a top, a peripheral wall, and hollow peripheral projections spaced apart and extending from substantially the junction of said top and peripheral wall, substantially as and for the purpose set forth.

5. As a new article of manufacture, a cap for a lubricant cup, the cap being composed 100 of sheet metal and having a top and a peripheral wall, and having portions of the metal forming the cap distorted to project from contiguous parts of said cap, at substantially the junction of said top and peripheral wall to provide a hand-engaging por-

tion, the outer extremities of said distorted portions being spaced apart from each other, substantially as and for the purpose described.

5 In testimony whereof, I have hereunto signed my name in the presence of two attesting witnesses, at Auburn, in the county

of Cayuga, in the State of New York, this 11th day of August, 1908.

GEORGE W. BOWEN.
